Clark M. Platt,
BY ATTORNEY

UNITED STATES PATENT OFFICE.

CLARK M. PLATT, OF WATERBURY, CONNECTICUT, ASSIGNOR TO THE
PATENT BUTTON COMPANY, OF SAME PLACE.

RIVET-SETTING MACHINE.

SPECIFICATION forming part of Letters Patent No. 394,722, dated December 18, 1888.

Application filed May 24, 1888. Serial No. 274,995. (No model.)

To all whom it may concern:

Be it known that I, CLARK M. PLATT, of Waterbury, in the county of New Haven and State of Connecticut, have invented a certain 5 new and useful Improvement in Rivet-Setting Machines, of which I declare the following to be a full, clear, and exact description, reference being had to the accompanying drawings, forming part of this specification.

10 This invention relates to an improvement in rivet and eyelet setting machines; and the invention consists in a rivet and eyelet setting machine with its several parts constructed and combined in the manner hereinafter particularly shown, described, and claimed.

15 In the accompanying sheet of drawings, Figure 1 is a side elevation of my rivet-setting machine; Fig. 2, an under side view of feed-ratchet and plate; Fig. 3, a perspective 20 view showing curvature of chute; Fig. 4, a top view of lower end of chute and section, showing details of receiver; Fig. 5, a cross-section in line *xx*, Fig. 3; Fig. 6, a cross-section in line *yy*, Fig. 3; Fig. 7, a plan or top view of receiver; 25 Fig. 8, an edge view of same.

Similar letters of reference indicate like parts in the several figures.

This invention relates particularly to that class of rivet and eyelet setting machines that 30 are provided with a reservoir in which the rivets or eyelets are placed in bulk and from which they descend by an inclined chute to a receiver, from which receiver they are driven into a garment by the action of a plunger. 35 Rivet and eyelet setting machines having this general construction are old, and need not, therefore, be particularly described, excepting so far as may be necessary to fully explain the construction and operation of my improvement. 40

two pivoted holders, *n*. These holders *n* are pivoted to the supporting-bar *G*, and they are constructed to close an opening, *o*, in that bar, practically forming the bottom of a cylindrical recess made by the flaring ends *k* of the jaws *f*, the opening *o* in the bar *G*, and conical recesses *r* in these holders *n*, which recess permits the introduction of the rivet's head and stem into the receiver. The holders are united 5 by a spring, *s*, which impinges against the sides of the holders, as shown in Figs. 7 and 8, and its elastic force permits the opening and closing of the holders when the plunger *E* of the machine drives through the receiver 10 the rivet contained therein, as before described. The rivet having passed through, the action of the spring again closes the holders' ends ready for the next rivet, and so on. These holders *n* are preferably made with 15 wings *p*, with which the holders may be operated by the fingers when it is desired to remove a rivet without employing the plunger for that purpose. To the under side of the bar *G* is fitted a spring, *H*, with a pivoted ring, 20 *t*, which acts as a clamp for holding the fabric in place during the operation of riveting the button thereon; but as this clamping device has already been patented to me in a previous patent I need not describe it any further. 25 The foregoing description of the twisted chute, combined with the rivet-receiver, substantially describes my improvement in rivet-setting machines, and the operation of the machine with these improvements is as follows: 30 The rivets are placed in bulk within the reservoir *C*. The heads of these rivets being the heaviest, they gravitate in the receiver head downward; but, as it is necessary that they should ultimately present their points 35 downward in order to thrust the rivet through the garment on which it is to be employed, some provision must be made for accomplishing this change in the position of the rivet, and numerous devices have been employed 40 to effect that change. In my present improvement, as the rivets leave the receiver head downward and so follow the course of the channel *a*, they are compelled to follow that channel throughout its half-turn or 45 50 to the twisted part *B*, and in so doing when they arrive at the end *d* of the chute they will have reversed their position, presenting themselves to the receiver *D* or the cup-shaped ends *k* of the jaws *f* of the receiver, within which the 55 head of each rivet is received, the stem of the

rivet passing downward through the hole *o* in the bar *G* and into the conical recess *r* of the holders *n*, and there it remains till the garment, with a button to be attached to it, is brought beneath the rivet and in the desired 60 position by the action of the anvil *F*, when the downward movement of the plunger *E* drives the rivet through the receiver and into the garment, as before stated, its point or lesser end being upset or clinched. 65

In my rivet-setting machine the well-known cut-off *J* is employed to deliver one rivet at a time to the action of the plunger.

In order to effect the simultaneous opening and closing of the jaws *f* and the holders *n*, 70 the bars *m* are employed to produce that result, when the holders *n* are operated by the wings *p*, as stated, and also to some extent by the action of the plunger, the bars being fixed at one end to the jaws *f*, and their other 75 ends in close contact with the sides of the holders *n*, and operating as levers when the holders *n* are pressed outward to force open the jaws *f*.

Having now described my invention, what I 80 claim as new, and desire to secure by Letters Patent, is—

1. In the receiver of a rivet-setting machine, the combination of the pivoted holders *n*, connected by the spring *s*, and the jaws *f*, 85 pivoted at *g* and connected by the spring *e*, said holders and jaws being secured to the arm *G* and so arranged that the opening between the ends *k* of said jaws registers with the conical recess *r*, formed in the holders, substantially as and for the purpose described. 90

2. In a rivet-setting machine, the combination of the following elements: the arm *G*, provided near its outer end with the hole *o*, the pivoted holders *n*, having the recess *r* formed 95 therein and connected by the spring *s*, and the pivoted jaws *f*, provided with the arms *m* and the flaring ends *k* and connected by the spring *e*, said holders and jaws being secured to said arm *G* and so arranged that the opening between the ends *k*, the hole *o*, and the recess *r* register each with the others and constitute the receiver *D* of the machine, substantially as and for the purpose described. 100

CLARK M. PLATT.

In presence of—

LUCIEN F. BURPEE,
JOHN P. KELLOGG.
